THREAD CUTTING TEMPLE FOR WEFT REPLENISHING LOOMS

Albert Cederlund, Worcester, and William E. Kimmel, Millbury, Mass., assignors to Crompton & Knowles Corporation, Worcester, Mass., a corporation of Massachusetts

Application January 17, 1958, Serial No. 709,490

22 Claims. (Cl. 139—303)

This invention relates to weft replenishing looms and more particularly to thread cutting temples, and it is the general object of the invention to provide the temples with a movable cutter blade always under positive control and with thread control means to prevent or permit cutting of a thread depending upon whether the thread is that of a stored shuttle or one involved in a weft replenishing operation.

Certain looms that have gone into general use employ a shuttle box at the magazine side of the loom, having at least two shuttle cells, which rise and fall during loom operation to receive or eject a shuttle. When weaving certain fabrics, it is necessary, because of pattern requirements, to store a shuttle in one of the cells by moving the cell into inactive position for a number of picks while the weft or thread of an active shuttle is being laid in the shed after which the stored shuttle again becomes active. During inactivation of the stored shuttle, the weft or thread associated therewith will extend from the selvage to the stored shuttle and during continued weaving will be moved forwardly into range of the temple cutter blades whereby cutting of the weft will occur and when next the stored shuttle becomes active no weft will be laid, and the loom will be stopped by the usual weft stop motion. It is therefore an important object of the invention to provide means to prevent cutting of the thread of a shuttle when the latter is to be stored at the magazine end of the loom for a number of successive picks.

Another object of the invention is to provide a thread guarding and guiding means effective not only to guard against cutting of the thread of an inactive shuttle, but also effective to guide the thread of an outgoing and incoming bobbin into thread cutting position incident and subsequent to a weft replenishing operation respectively.

Still another object of the invention is to make the thread guarding and guiding means L-shaped having a rearwardly facing notch between the vertical and horizontal parts thereof, and to mount said means between the selvage of the fabric being woven and a movable thread cutter blade, such that the horizontal part extends toward and supports the selvage to guide the threads extending therefrom into said notch, and the vertical part coacts with a stationary cutter blade to frictionally hold the movable blade and prevent movement thereof until acted upon by blade actuating means interposed between one end of the movable blade and the lay.

A further object of the invention is to prevent sluggish operation of the movable blade by eliminating the springs or weights commonly used in connection with the movable blade and the force transmitting parts that move the blade.

A further object of the invention is to actuate the movable blade positively for a cutting operation by said blade actuating means while the lay is moving rearward-

2

ly and to return said blade positively by said means to open or noncutting position while the lay is moving forwardly.

A further object of the invention is to provide the said blade actuating means with a force transmitting member effective to actuate the movable blade positively and capable of being freely moved in a forward direction to prevent breakage of the temple, said means, or said blade when the temple is moved forwardly in the usual manner because of a misplaced shuttle.

A still further object of the invention is to provide the blade actuating means with a connection whereby the time of the cutting operation may be varied.

Other objects of the invention will appear as the description proceeds, and in order that the invention may be clearly understood reference is made to the accompanying drawings which illustrate by way of example three embodiments of the invention and in which:

Fig. 1 is a front elevation of the right-hand side of a weft replenishing loom having the preferred form of the invention applied thereto,

Fig. 2 is an enlarged plan view looking in the direction of arrow 2, Fig. 1, parts being broken away, and parts being in section, showing the outgoing thread in two positions,

Fig. 3 is an enlarged side elevation of the temple head looking in the direction of arrow 3, Fig. 2,

Fig. 4 is a rear elevation of the temple head on line 4—4, Fig. 3,

Fig. 5 is a horizontal section on line 5—5, Fig. 4,

Fig. 6 is a fragmentary perspective view of the cutter blades and the thread guarding and guiding means,

Fig. 7 is a longitudinal vertical section on line 7—7, Fig. 2, certain parts being omitted, showing the movable blade in open or noncutting position with the lay at front center position,

Fig. 8 is a sectional view on line 8—8, Fig. 7,

Fig. 9 is a view similar to Fig. 7 but showing the lay at back center position and the movable blade in closed position but slightly beyond the actual thread cutting position,

Fig. 10 is a view similar to the lower portion of Fig. 7 but showing the first modification of the invention,

Fig. 11 is a longitudinal vertical section showing the second modification of the invention and the movable blade and lay in two different positions,

Fig. 12 is a view looking in the direction of arrow 12, Fig. 11,

Fig. 13 is a diagrammatic plan view showing how the thread guarding and guiding means prevents cutting of the thread of a stored shuttle, and

Fig. 14 is a diagrammatic plan view showing the new or incoming thread of a transferred bobbin in position to be cut.

Referring particularly to Figs. 1, 2 and 7, right and left-hand loomsides 1 and 2 respectively support therebetween a breastbeam 3 over which the cloth C passes to the usual cloth roll, not shown. The loomsides also support a rocker shaft 4 on which is mounted a pair of reciprocating laywords 5 (only one of which is shown) having fixed thereto the usual lay L and reed R for back and forth movement during loom operation.

The lay carries a lay end 6 which supports and guides a gang G of shuttle boxes having upper and lower cells 7 and 8 respectively to receive into or have ejected therefrom shuttles S1 and S2 as the case may be. The gang G is lifted and lowered in well-known manner by a box lifter rod 9 under control of a flexible connector 11 operatively connected to rod 9 as at 12 from which the flexible connector extends over a pulley 13 and thence to the head mechanism (not shown) on the opposite end of the loom. During loom operation either

of the cells 7 or 8 will be moved by rod 9 to so-called running position to receive or eject a shuttle and when a shuttle is to be stored for a number of successive picks because of pattern requirements the shuttle will be picked into cell 7 and the gang G will be moved to the dotted line position, Fig. 1, whereby cell 3 will be in running position to receive or pick a shuttle.

A weft detector generally indicated at D, Fig. 1, is mounted on a slide 14 and is guided for vertical movement by a stationary arm 15 depending from a reserve bobbin magazine M. The upper end of a rod 16 is connected to slide 14 and the lower end is connected to an arm 17 fast on rod 9. The weft detector D is aligned with cell 7 and rises and falls with gang G, but does not have a back and forth motion as does the gang. Detection of weft exhaustion and subsequent transfer of a bobbin from the magazine into an empty shuttle can occur only when the lay is at front center position, that is, detection will occur when the gang G is approaching the dotted line position shown in Fig. 1, and transfer will occur on the front center following detection with the gang in said position.

The matter thus far described is of common construction and operates in the usual manner.

The invention as set forth herein contemplates the use of a temple generally indicated at T and, except as noted hereinafter, is of usual construction having a pair of caps 18, temple rolls 19, only one of which is shown, see Fig. 4, a head 21, a shank 22 and a casing 23. The temple is mounted for lateral and back and forth adjustment on a plate 24 fast on the breastbeam 3. Shank 22 supports rear cap 18 and head 21 and extends into the casing 23 wherein the usual spring (not shown) urges the shank rearwardly. When a shuttle is trapped or misplaced (see dotted position of shuttle in Fig. 2) between the rear R and the head 21, continued forward motion of the lay will cause the shuttle to move the shank 22 and parts supported thereby forwardly to prevent damage or breakage to either the shuttle, the temple, or both. Under these conditions the loom will be automatically stopped by well-known protector mechanism in the usual manner after which the shuttle will be manually placed in the proper shuttle box. Removal of the shuttle from between the reed and the head will cause the then compressed spring in the casing to expand to move the shank rearwardly until the rear cap 18 and head 21 are back in their normal rear position, whereby the loom will again be ready for operation.

In carrying the preferred form of the invention into effect, the head 21 is provided with a vertical recess 25 extending longitudinally through the head and providing an opening at the bottom thereof as seen for instance in Fig. 7. Recess 25 has narrow portions 25a and 26, Fig. 4, to receive the upper ends of a stationary cutter blade 27 and an L-shaped member 28 respectively. Blade 27 and member 28 are mounted within the recess or slot 25 and are held fast to the head by a screw 29 threaded into the head 21. Member 28 has a vertical and horizontal leg 31 and 32 respectively and a rearwardly-facing continual notch 33 between the legs to receive the thread of a stored shuttle and the threads of an incoming and outgoing bobbin respectively. Leg 32 is at right angles to leg 31 and extends toward the cloth C and partially under the latter to support the selvage and to guide the threads extending therefrom into notch 33. Member 28 may be considered thread control means or more particularly thread guarding and guiding means.

As viewed in Fig. 4, stationary cutter blade 27 and L-shaped member 28 are spaced laterally from each other and receive frictionally therebetween the rear end 34 of a movable cutter blade generally indicated at 35 pivoted at 36 on the head 21. A cutting edge 37 on movable blade 35 cooperates with a cutting edge 38 on blade 27, see Fig. 6, to have a cutting operation while the lay L moves rearwardly.

Referring particularly to Figs. 7, 8 and 9, the lay L supports a rod 39 journalled in brackets 41 fixed to the lay L in any approved manner. Rod 39 moves in an arcuate path generally indicated by the numeral 40 concentric with the axis of rocker shaft 4 and is operatively connected to a lever generally indicated at 42 having upper and lower arms 43 and 44 respectively, spaced from each other by collars 45 and held rigid with respect to each other by bolts 46 passing through the arms and collars and fastened thereto by nuts 47. Arm 43 has an arcuate portion 48 which partially surrounds a tubular shaft 49, and arm 44 has a straight end portion 51 which contacts shaft 49, both of said portions forming a bearing for pivotal movement on shaft 49. Arm 44 has a rearwardly extending straight part 52, a curved part 53, and a forwardly extending straight part 54, said parts forming an open end straight slot 55 to receive the rod 39.

Arms 43 and 44 have clamped thereto a rod 56 the upper end of which is pivotally connected as at 57 to the lower end of a link or force transmitting member 58 having pivotal connection at its upper end as at 59 to arm 61 of movable cutter blade 35. The lower end of rod 56 extends downwardly to one side of arms 43 and 44 and passes through an eyebolt 62 having a threaded shank 63 to receive a washer 64 and a nut 65 on the side of arms 43 and 44 opposite to that of rod 56, see Fig. 8. Turning of nut 65 in one direction will draw the lower end of rod 56 and the washer 64 toward each other to effectively clamp arms 43 and 44 therebetween. Rod 56, therefore, is held rigid with respect to arms 43 and 44. Turning of nut 65 in the opposite direction will loosen the clamping relationship above described, whereby rod 56 may be vertically adjusted with respect to eyebolt 62 and the latter and washer adjusted with respect to arms 43 and 44 after which clamping is again effected by turning of nut 65. By the adjustments described above, the time of thread cutting may be varied and controlled. Rod 39, lever 42, and the connection including rod 56, eyebolt 62, washer 64 and nut 65 may be considered primary actuating means, secondary actuating means, and control means respectively, said means together with link 58 being generally considered as blade actuating means.

In the modified form of the invention shown in Fig. 10 several of the parts therein are the same as described in reference to the preferred form of the invention, and it is deemed only necessary to describe those parts that are different. A lever generally indicated at 66, similar in certain respects to lever 42, has a rearwardly extending arcuate portion 67, a curved end portion 68, and a forwardly extending arcuate portion 69. Portions 67 and 69 are joined to end portion 68 by arcuate curves 71 and 72 respectively to define an open end sinuous slot 73 to receive rod 39. Portion 67 and 69 are parallel to path 40, whereas portions 71 and 72 are substantially oppositely curved to path 40 and portions 67 and 69 for a purpose to be described hereinafter.

In the modified form of the invention illustrated in Figs. 11 and 12, the lay L supports a pair of brackets 74 to which a stub shaft 75 is secured by set screws 76. A block 77 is mounted on shaft 75 intermediate brackets 74 for angular movement thereon and has a rear part that snugly fits between a pair of collars 78 fast on shaft 75 to prevent lateral displacement of block 77 as viewed in Fig. 12. A rod 79, similar in construction to rod 56, has its upper end pivoted as at 81 to the above described movable cutter blade 35 while a substantial part of the lower end is slidable in a bore 82, see Fig. 11, in block 77. An upper collar 83 adjustably secured to rod 79 coacts with block 77 to move rear end 34 of blade 35 downwardly to open or noncutting position when the lay moves forwardly and a lower collar 84 also adjustably secured to rod 79 cooperates with block 77 to move said rear end 34 upwardly to have a cutting operation with stationary blade 27 when the lay is moving rear-

wardly. Rod 79, collars 83 and 84, block 77 and shaft 75 may be generally considered as blade actuating means for the modified form of the invention.

During loom operation the lay L will travel back and forth between its extreme forward or front center position and its extreme rearward or back center position. As the lay moves rearwardly from front center, see Fig. 7, rod 39 will travel in slot 55 along path 40 and contact straight part 54 of lever 42 to cause the latter to be lowered whereby motion is transmitted through rod 56 and link 58 to blade 35 to effect raising of end 34 for a cutting operation. Cutting of a thread, however, will not occur until the lay is in the latter part of its rearward stroke due to the fact that the cutting edges 37 and 38 of blade 35 and 27 respectively are vertically spaced from each other when the lay is at front center, see Fig. 6. Cutting will actually occur at or near back center depending upon where the connection or rod 56 is with respect to arms 43 and 44.

When the lay is at back center, Fig. 9, end 34 will be at the end of its upward stroke, or in closed position with respect to blade 27 and as the lay moves forwardly toward front center rod 39 will contact straight part 52 to effect a reversal of the motion above described. When the lay reaches front center end 34 will be at the end of its down stroke or in open position with respect to blade 27.

In the first modification, see Fig. 10, rod 39 when moving rearwardly from front center will have no effect on blade 35 during the greater part of its rearward motion. Arcuate portions 67, 69 and the left-hand part of slot 73 are made parallel to path 40 so that end 34 will not move to closed or cutting position until rod 39 has entered the right-hand part of slot 73 and has contacted arcuate curve 72 whereupon continued rearward motion of rod 39 will depress lever 66 to move end 34 to cutting position at or near back center. During the first part of the forward stroke of the lay, rod 39 will engage arcuate curve 71 and raise lever 66 to return end 34 to open or noncutting position. Continued forward motion of the rod in slot 73 will have no effect on end 34 as was the case when the rod was moving rearwardly in the slot.

In the second modified form of the invention, Figs. 11 and 12, end 34 will be moved in a manner similar to that described in the first modification but will derive its cutting motion from block 77 when the latter engages collar 84 near back center position to exert a pull on rod 79 as the lay continues to move backwardly. End 34 will be returned to open or noncutting position at front center by engagement of block 77 with collar 83. Rod 79 has a part of its lower end freely slideable in bore 82 and the relationship between the latter and said part is such that block 77 can "find" or locate itself angularly with respect to shaft 75 as the lay swings back and forth. However, when block 77 engages collars 83 and 84, angular movement of the block will stop and a push or pull force will be exerted on rod 79 respectively to move end 34 to open and then to closed position. Collars 83 and 84 may be adjusted along rod 79 to vary and control the time of thread cutting.

Fig. 13 diagrammatically illustrates the manner in which cutting of a thread of a stored shuttle is prevented. After shuttle S1 or any other shuttle has entered cell 7, gang G will be raised to the dotted line position, Fig. 1, and remain there for a number of successive picks while cell 8, now in running position, will receive and eject shuttles for continued weaving. Thread TH, Fig. 13, will extend from shuttle S1 to the selvage of cloth C, and at the start of the storing period will be in the full line position. As the loom continues to weave the cloth will be moved forwardly by the takeup mechanism (not shown, but well known) and thread TH will be guided over horizontal leg 32 and into notch 33 to assume the dotted line position. That part of the thread extending from the notch to the shuttle will be rearward of cutting edges 37

and 38 and when a cutting operation occurs at or near back center, thread TH will not be cut as would be the case if the latter extended from the point of anchorage (dotted line position) at the selvage directly to the stored shuttle. It is to be understood that the dotted line position of thread TH is only one of many positions it can assume as weaving progresses during storage of a shuttle. When the lay is at front center, part of the thread will be over and under cutting edges 37 and 38 respectively, but the thread will not be cut since, in all forms of the invention, cutting can only occur at or near back center position of the lay.

Referring particularly to Fig. 2, the thread or weft OT is shown in full and dotted line positions which represent the positions taken by the thread incident and subsequent to a weft replenishing operation respectively. Detection of weft exhaustion followed by a weft replenishing operation and the mechanisms therefor are well known in the art and further elaboration thereof is believed unnecessary. It is deemed sufficient to say that just prior to the insertion of a full bobbin into a shuttle the usual thread cutter 90 will cut the outgoing thread OT at the shuttle eye while the usual pneumatic thread remover 91 is over and adjacent the thread (dotted line position, Fig. 2), to pick up that part of the thread extending from the remover to the shuttle eye. After the transferring operation has been completed, the lay will start rearwardly and the detector and weft replenishing mechanisms will return to their normal position as will the remover which will move from the dotted to the full line position, see Fig. 2. In the present instance the outgoing thread, shown in dotted lines, will extend from the remover to the selvage and as weaving continues that portion of the thread adjacent the selvage will be guided over horizontal part 32 and into notch 33 to insure placing of the thread between cutting edges 37 and 38 after which cutting of the thread will occur at or near back center position of the lay as above described.

After a full bobbin has been inserted into the shuttle the gang G will eventually shift so that cell 7 will be in running position after which shuttle S1 will be picked to the other side of the loom. The new or incoming thread IT will extend from the usual thread holder 92 to the cloth C, and during the beating up of the lay immediately after picking of the replenished shuttle, thread IT will be engaged by a thread pusher 93 to place the thread in the notch of a retaining hook 94. The incoming thread will assume the position shown in Fig. 14 having a portion thereof over horizontal part 32 in notch 33 and between cutting edges 37 and 38. Thread IT will be cut in a manner similar to that described for cutting the outgoing thread OT. The thread holder, pusher and hook are well known and for a further understanding of their operation, reference is made to Patent No. 2,416,803.

In all forms of the invention, end 34 of blade 35 is frictionally held between stationary blade 27 and L-shaped member 28 in open or closed position until acted upon by the blade actuating means as described hereinbefore. By frictionally holding end 34 in open or closed position, needless vertical motion of end 34 is prevented, and a thread cutting operation cannot occur at the wrong time because of loom vibration or the tendency of the weight of the parts depending from pivots 59 or 81 to turn blade 35 counterclockwise, see Figs. 7 and 11.

As stated before, a shuttle may be trapped or misplaced between the reed R and the temple head 21. This comes about when a shuttle enters either shuttle cell 7 or 8 and rebounds toward the cloth to assume the dotted line position in Fig. 2 because of a strong pick from the opposite side of the loom or malfunction of the usual shuttle holding binder associated with each box. At this time the lay is moving forwardly to cause the shuttle to move the temple head to the dotted line position shown in Fig. 7. Because link 58, in the pre-

ferred and first modified forms of the invention, is free to pivot as at 57 and 59, it will also move forwardly thus preventing breakage of the temple, movable blade 35, and any of the parts of the blade actuating means.

In the second modified form of the invention a misplaced shuttle will have the same effect on the temple head as that described for the other two forms of the invention, but in this case collar 83 on rod 79 will have a component of movement downwardly as the lower part of the latter swings rearwardly from pivot 81. This movement urges block 77 counterclockwise about shaft 75 to prevent breakage of the temple, blade 35, and any of the parts of the blade actuating means pertaining to this modified form of the invention.

Although a description of the control of the weft of a stored shuttle and the outgoing and incoming threads was made with respect to shuttle 81 only, it is to be understood that the invention is not limited to controlling just these threads but that other threads of other shuttles will be controlled in the same manner when any of them is to be stored or is to have its weft replenished.

From the foregoing it will be seen that the invention sets forth simple means to guard against cutting the thread of a stored shuttle and to guide the outgoing and incoming threads relative to a weft replenishing operation into position to be cut by the temple blades. Also, simple means have been provided whereby the movable blade is always under positive control in all forms of the invention. This positive control is attained by eliminating the use of springs and having positive connections throughout the blade actuating means from the lay to the movable blade. In addition, end 34 is positively held between blade 27 and member 28 frictionally to prevent motion of said end until acted upon by the blade actuating means.

In all forms of the invention the cutting operation occurs at or near back center position of the lay when the latter is moving rearwardly, and resetting or opening of the movable blade takes place while the lay is moving forwardly. In the case of the preferred form the full forward stroke of the lay resets the blade, and in the first and second forms the first and latter part of the forward motion of the lay respectively resets the blade. By having the cutting operation take place at or near back center, and resetting of the movable blade at or before front center, cutting of the thread of an active shuttle is prevented when the lay approaches front center and the thread lies in the approximate position as that shown for the outgoing thread (full line position) in Fig. 2.

The invention also provides simple control means or connections whereby the latter may be adjusted with respect to levers 42 and 66 to vary and control the time of thread cutting, said means including rod 56, eyebolt 62, washer 64, and nut 63 for the preferred and first modified forms of the invention. In the second modified form, collars 83 and 84 are adjustable with respect to rod 79 to vary and control the time of thread cutting.

Although the connections from the movable cutter blade to the lay are positive in nature, the invention in all forms provides simple means to prevent fracture or breakage of the temple, movable blade 35 and the blade actuating means when a shuttle is misplaced. In the first two forms of the invention link 58 is capable of moving forwardly with the temple head if the latter is thus moved because of a misplaced shuttle. In the third form of the invention movement of the temple head forwardly will cause the lower part of rod 79 to swing rearwardly from pivot 81 to effect lowering of collar 83 and attendant angular down motion of block 77 to relieve strain on the blade actuating means, thereby preventing fracture or breakage thereof.

Having now particularly described and ascertained the nature of the invention and in what manner the same is to be performed, it will be seen that changes and

modifications may be made therein by those skilled in the art without departing from the spirit and scope of the invention and that the invention is not limited to the details herein disclosed, but what is claimed is:

5. 1. In a weft replenishing loom having a rearwardly and forwardly reciprocating lay, a magazine at one end of the loom, a shuttle box at the magazine end of the loom having at least two shuttle cells either of which is capable of receiving a shuttle to be stored therein for a number of successive picks, and a thread cutting temple having a head and a stationary cutter blade, a movable thread cutter blade pivotally mounted in said head and always under positive control of said lay to co-act with said stationary cutter blade to have a thread cutting operation when the lay moves rearwardly and a resetting operation when the lay moves forwardly, thread control means substantially within said head to prevent cutting of the thread of a stored shuttle and to guide the threads involved in a weft replenishing operation into the cutting range of said blades incident and subsequent to said weft replenishing operation respectively, and blade actuating means to positively move said movable blade for said cutting and resetting operations, said blade actuating means having positive connections between said movable blade and said lay.
10. 2. The loom set forth in claim 1 wherein said thread control means is an L-shaped member fixed with respect to and mounted substantially within said head adjacent the movable cutting blade and between said blade and the cloth being woven.
15. 3. The loom set forth in claim 1 wherein said thread control means is provided with a notch facing rearwardly of the loom to receive the thread of a stored shuttle to guard against severing of the thread and to also subsequently receive individually the threads of the outgoing and incoming bobbin and guide and maintain said threads into range of the cutting blades during and following a weft replenishing operation respectively.
20. 4. The loom set forth in claim 1 wherein said thread control means has a horizontal leg extending laterally from a vertical leg toward and beneath the cloth to guide into said notch not only the thread extending from the selvage to a stored shuttle but also the outgoing and incoming threads involved in a weft replenishing operation.
25. 5. In a weft replenishing loom having a reciprocating lay, a temple at one end of the loom having a head, a pair of cutting blades within said head having a thread cutting operation when the lay moves rearwardly, a shuttle box at said end of the loom having at least two shuttle cells either of which is capable of receiving a shuttle to be stored therein for a number of successive picks, and thread control means fixed with respect to said head to prevent cutting of the thread of a stored shuttle when said blades have a cutting operation.
30. 6. The loom set forth in claim 5 wherein said means includes a vertical leg fast with respect to the head, a horizontal leg extending laterally from said vertical leg toward and under the cloth being woven, said means having a rearwardly facing notch common to said legs, said horizontal leg being effective to guide said thread into said notch as the cloth moves forwardly during loom operation.
35. 7. In a weft replenishing loom having a rearwardly and forwardly moving lay, a shuttle box at the magazine end of the loom, a thread cutting temple at said end having a head and a movable and a stationary cutter blade substantially therein to have a thread cutting operation when the lay moves rearwardly, and thread control means within said head to guide the outgoing thread extending from the selvage to a substantially depleted shuttle in said shuttle box into the range of said cutting blade incident to a weft replenishing operation.
40. 8. The loom set forth in claim 7 wherein said means is a member fixed with respect to said head and having
45. 9. The loom set forth in claim 7 wherein said means is a member fixed with respect to said head and having
50. 10. The loom set forth in claim 7 wherein said means is a member fixed with respect to said head and having
55. 11. The loom set forth in claim 7 wherein said means is a member fixed with respect to said head and having
60. 12. The loom set forth in claim 7 wherein said means is a member fixed with respect to said head and having
65. 13. The loom set forth in claim 7 wherein said means is a member fixed with respect to said head and having
70. 14. The loom set forth in claim 7 wherein said means is a member fixed with respect to said head and having
75. 15. The loom set forth in claim 7 wherein said means is a member fixed with respect to said head and having

a leg capable of guiding said thread into a slot effective to maintain said thread in a position to be cut by said blades when the latter have a cutting operation.

9. In a weft replenishing loom having a rearwardly and forwardly reciprocating lay, a reserve bobbin magazine at one end of the loom and a thread holder for the threads of the bobbins, a shuttle box at the magazine end of the loom, a thread cutting temple at said end having a head and a movable and stationary cutter blade substantially therein having a thread cutting operation when the lay moves rearwardly, and thread control means within said head to guide the incoming thread extending from the selvage to said thread holder into the range of said cutting blades subsequent to a weft replenishing operation.

10. The loom set forth in claim 9 wherein said thread control means includes a member having means to receive and maintain said thread in said range of said blades, and means to guide said thread into said receiving means.

11. The loom set forth in claim 10 wherein said receiving means is a rearwardly facing notch in said member having vertically and horizontally disposed parts.

12. The loom set forth in claim 10 wherein the guiding means is a horizontal leg forming part of said member.

13. In a loom having a reciprocating lay and a thread cutting temple with a head provided with a movable and a stationary cutter blade for cooperation with each other to sever the thread, blade actuating means to positively actuate said movable blade to closed cutting position and to open noncutting position, means fixed to said head and laterally spaced from and cooperating with said stationary blade to frictionally hold therebetween said movable blade in said closed and open positions to prevent said movable blade from having a movement to effect cutting of said thread until acted upon by said blade actuating means.

14. The loom set forth in claim 13 wherein said blade actuating means includes primary actuating means on said lay effective when moving in one direction to close said movable blade for a cutting operation and effective when moving in the opposite direction to open said movable cutter blade, secondary actuating means pivotally mounted at one end thereof and having its other end operatively connected to said primary means, and control means between said ends capable of being adjusted with respect to said secondary means to vary the time of said cutting operation.

15. The loom set forth in claim 13 wherein said blade actuating means is between the lay and the movable blade.

16. The loom set forth in claim 14 wherein said primary actuating means is a rod on said lay having positive connections with said secondary means.

17. The loom set forth in claim 14 wherein said secondary means is a lever pivotally connected at one end thereof to the loom frame and having a slot at its other end to receive said primary acting means.

18. The loom set forth in claim 14 wherein said cutter control means is between said ends of said secondary means and includes an adjustable connection whereby the time of said cutting operation can be varied and controlled.

19. In a loom having a reciprocating lay and a thread cutting temple provided with a movable cutter blade, blade actuating means having positively acting connections between said lay and said blade and including thread cutter control means, and force transmitting means capable of having normal motions to close and open said blade and capable of having an abnormal motion to prevent breakage of said temple and said actuating means in the event a misplaced shuttle moves said temple forwardly.

20. The loom set forth in claim 19 wherein said force transmitting means is a link between said movable blade and said thread cutter control means, said link being pivoted at one end thereof to said control means and pivoted at its other end thereof to said movable blade.

21. In a loom having a lay and a temple provided with a stationary cutting blade for cooperation with a movable cutting blade capable of closing to effect a thread cutting operation when the lay moves rearwardly and capable of opening to reset position when the lay moves forwardly, and actuating means for the movable blade including a system of force transmitting parts effective to close the movable blade when the lay is in the latter part of said rearward motion and effective to open the blade when the lay is in the first part of its forward motion.

22. In a loom having a lay and a temple provided with a stationary cutting blade for cooperation with a movable cutting blade capable of closing to effect a thread cutting operation when the lay moves rearwardly and capable of opening to position when the lay moves forwardly, and the actuating means for the movable blade including a system of force transmitting parts effective to close the movable blade when the lay is in the latter part of said rearward motion and effective to open the blade when the lay is in the latter part of its forward motion.
